DR 7 19,127

UNITED STATES PATENT OFFICE.

EDWARD L. CALEY, OF PHILADELPHIA, PENNSYLVANIA, ASSIGNOR TO GILBERT COMBS, JOHN BAWDEN, AND JOHN H. BAWDEN, OF FREEHOLD, NEW JERSEY.

DESIGN FOR A FIRE-PLACE LINING.

SPECIFICATION forming part of **Design No. 19,127**, dated June 4, 1889.

Application filed January 9, 1889. Serial No. 295,887. Term of patent 7 years.

To all whom it may concern:

Be it known that I, EDWARD L. CALEY, a citizen of the United States, and a resident of Philadelphia, Pennsylvania, have invented a new and original Design for a Fire-Place Lining, of which the following is a specification.

My design for a fire-place lining is fully shown in the accompanying photographs.

The design comprises both the back and side plates.

The general feature of the design is the block pattern.

Figure 1 is a general view of the fire-place lining; and Fig. 2 is an enlarged view, showing the blocks in detail.

The decoration of the back and side plates is the same, and consists of a series of quadrangular blocks formed by beveled grooves,

so that each block is beveled on its four sides, and each block has a central circular projection surrounded by a ring, and radiating from this ring is a series of raised lines. The radiating lines at the corners are somewhat longer than those at the sides, forming a quadrangular outline.

I claim —

The design for a fire-place lining, substantially as described, and as shown in and by the accompanying photographic illustrations.

In testimony whereof I have signed my name to this specification in the presence of two subscribing witnesses.

EDWARD L. CALEY.

Witnesses:

WILLIAM D. CONNER,
HARRY SMITH.
